UNITED STATES PATENT OFFICE.

WILLIAM HENRY SMITH, OF PURLEY, ENGLAND.

RECEPTACLE.

No. 835,645.

Specification of Letters Patent.

Patented Nov. 13, 1906.

Application filed January 19, 1906. Serial No. 296,878.

To all whom it may concern:

Be it known that I, WILLIAM HENRY SMITH, a subject of the King of England, residing at Purley, in the county of Surrey, England, have invented certain new and useful Improvements in Receptacles, of which the following is a specification.

This invention relates to improvements in air-tight boxes, jars, or other receptacles—such, for example, as the metal boxes used for storing sensitized photographic paper.

One feature of this invention consists in providing a simple and efficient device for tightly closing the receptacle or for producing an air-tight joint round the edges of the lid or cover, and in a specific form of air-tight box embodying this invention and containing a desiccator a novel arrangement of the box is provided.

The closing device I have hitherto employed comprises a lid having a packing-ring at its edge and radially-movable segments arranged within the ring and connected by toggle-arms with a central movable member by which the packing-ring may be pressed into close contact with the receptacle.

According to this invention the toggle-arms and separate segments are dispensed with, and a dished frame, having resilient radial arms engaging the packing-ring at their ends, is arranged to be pressed downward in the center, so as to force the ends of the arms outward. The frame may be of sheet metal, cut or slotted so as to form the radial arms, and the arms preferably terminate in segmental pieces which are practically in contact with one another, so as to produce an even pressure all round the packing-ring. When the pressure is removed from the center of the frame, the resilient arms cause the frame to recover its original form, thus withdrawing the segmental pieces and releasing the closing device.

In one method according to this invention for pressing down the center of the frame a rod fixed at its lower end to the base of the lid projects upward through the center of the frame, and a handle pivoted thereto carries a cam arranged to force down the center of the frame when the handle is rotated. Preferably the cam has a flat end, so that when the handle is turned, say, in a horizontal position the center of the frame is forced down and retained in that position.

In arranging an air-tight box containing a desiccator according to this invention a

hygroscopic agent is placed in a flat pan or tray fitting easily into the bottom of the box, and the pan is covered with a perforated plate. To hold these parts in place and to prevent paper from sliding down between the perforated plate and the side of the box, a cylindrical liner is inserted in the box, so as to rest on the perforated plate. The top of this liner reaches nearly to the upper edge of the box and serves as an abutment on which the lid or cover may rest.

In the accompanying drawings, Figure 1 is a vertical section of a cylindrical receptacle provided with a closing device embodying this invention and particularly adapted for containing photographic paper. Fig. 2 is a similar view showing the closing device in its gripping position. Fig. 3 is a plan showing the dished frame. Fig. 4 is a vertical section illustrating the novel internal arrangement of a box containing a desiccator. Fig. 5 is an elevation showing a modified form of lid, and Fig. 6 illustrates in plan the application of this invention to a rectangular receptacle.

Like letters indicate like parts in all the figures of the drawings.

Referring to Figs. 1, 2, and 3, the receptacle itself A has an inner abutment or flange A' near the top to receive the lid. The lid comprises a disk B, say of sheet-zinc, turned upward at its edges. Within this and above it is a second disk B', and between the disks is retained a packing-ring C, of india-rubber or the like, conveniently L-shaped in cross-section. This lid may be an easy fit in the top of the receptacle A. The lid has a rod D projecting upwardly from its center, the connection D' between the rod D and the disk B being air-tight. Resting on the top of the lid and within the packing-ring is a dished frame E, of resilient material, such as brass. This is in the form of a flat cone with its base resting on the disk B', and the central rod D passes upward through the apex or center E' of the frame, a steel washer F being preferably placed over the center of the frame. Various methods of cutting or slotting the frame E may be employed; but conveniently the metal is cut away, so as to leave a large number of narrow arms, which are extended at their ends to form segmental pieces E' of such a size that there is a practically continuous series of segments within the packing-ring C. Pivoted to the top of the central rod D is a handle G, at the bottom of which are lugs G', which form a substantially oblong

cam with flat ends, the arrangement being such that when the handle G is rotated into a horizontal position in either direction the center E' of the frame is forced downward, and 5 the flat end of the cam G' engaging the washer F prevents the frame E from returning to its normal position. The closing device may be provided with a cover H, secured in place above the frame by screws H', screwing into the ends of posts H², projecting up 10 from the disk B'.

In the form shown in Fig. 1 the desiccator is arranged in a known manner in the box A. The hygroscopic agent J, such as calcium 15 chlorid, is placed in a flat pan K, and the pan is covered by a perforated plate K', screwed to the pan. The edges of the plate K' rest on a flange A² near the bottom of the box.

Referring to Fig. 4, which illustrates a novel 20 arrangement, the pan K fits loosely in the box A and is covered with a perforated plate K'. The cylindrical liner L rests on the plate, and the top of the liner reaches nearly to the edge of the box, thus serving as an 25 abutment on which the disk B may rest.

Referring to Fig. 5, a flange or abutment inside the box may be dispensed with, and the cover H may be extended to form a flange H', which engages the top of the box A.

This invention is applicable to receptacles 30 of various shapes, and Fig. 6 shows the form of frame E which may be used for a rectangular box. The arms of the frame E in this case terminate in straight branches E³ and in 35 corner-pieces E⁴, both engaging the packing-ring C.

It is to be understood that the details of construction and arrangement may be varied without departing from this invention.

40 What I claim as my invention, and desire to secure by Letters Patent, is—

1. The combination of a receptacle having an open mouth, a lid therefor, an expansible band around the lid, a dished frame on the 45 lid having resilient radial arms engaging the expansible band at their ends, a central rod fixed to the lid and projecting through the frame and a handle pivoted to the rod and carrying a cam arranged to force down the 50 center of the frame when the handle is turned.

2. The combination of a receptacle having an open mouth, a lid therefor, an expansible band around the lid, a dished frame on the lid having resilient radial arms engaging the 55 expansible band at their ends, a central rod fixed to the lid and projecting through the frame, a handle pivoted to the rod and carrying a cam having a flat end so that the center of the frame may be forced down and retained when the handle is turned.

3. The combination of a receptacle having an open mouth, a lid therefor, an expansible

band around the lid, a dished frame on the lid having resilient radial arms terminating in segmental pieces engaging the expansible 65 band, a central rod fixed to the lid and projecting through the frame and a handle pivoted to the rod and carrying a cam arranged to force down the center of the frame when the handle is turned.

4. The combination of a cylinder closed at the bottom and open at the top, a metal lid therefor, an india-rubber packing-ring projecting up from the periphery of the lid and secured thereto, a dished frame of resilient 70 metal having a plurality of arms engaging the packing-ring at their ends, a rod projecting from the disks through the apex of the frame and a handle pivoted to the rod and carrying a cam engaging the top of the frame 80 whereby when the handle is turned the center of the frame is forced down and presses the packing-ring into contact with the receptacle.

5. The combination of a cylinder closed at 85 the bottom and open at the top and a lid comprising a metal disk turned up at its edges, a second metal disk above and within the first and secured thereto, an india-rubber packing-ring projecting from the periphery 90 of the disks and held between them, a dished frame of resilient metal having a plurality of arms extended at their ends to form a continuous series of segmental pieces engaging the inside of the packing-ring, a cover secured on the lid over the frame, a rod projecting from the disks through the apex of the frame and the cover, a handle pivoted to the rod and carrying a cam having a flat end and engaging the top of the frame, whereby 100 when the handle is turned the center of the frame is forced and held down pressing the packing-ring into contact with the receptacle.

6. In an air-tight receptacle the combination with a cylinder closed at the bottom and open at the top, a desiccator resting on the bottom, a cylindrical lining within the cylinder and resting on the desiccator, an impervious lid resting on the lining at the top of the cylinder, an expansible band round the lid, a dished frame on the lid having resilient radial arms engaging the expansible band at their ends and means for pressing down the center of the frame to move the ends of the 110 arms outward and force the expansible band into contact with the cylinder.

In testimony whereof I have signed my name to this specification in the presence of two subscribing witnesses.

WILLIAM HENRY SMITH.
